UNITED STATES PATENT OFFICE

138,712

DESIGN FOR A ROTARY HOE UNIT OR THE LIKE

George E. Karl, Liberty, Ind.

Application March 29, 1944, Serial No. 113,062

Term of patent 14 years

(Cl. D39—1)

To all whom it may concern:

Be it known that I, George E. Karl, a citizen of the United States and a resident of Liberty, in the county of Union and State of Indiana, have invented a new, original, and ornamental Design for a Rotary Hoe Unit or the like, of which the following is a specification, reference being had to the accompanying drawing, forming a part thereof.

Figure 1 is a side elevation of a rotary hoe unit, showing my new design; and

Figure 2 is a sectional view on the line 2—2 thereof.

I claim:

The ornamental design for a rotary hoe unit or the like, substantially as shown.

GEORGE E. KARL.
